UNITED STATES PATENT OFFICE

GUIDE FLANGE FOR RAILWAY VEHICLES

Pierre Marcel Bourdon, Paris, France, assignor to
Michelin et Cie., Clermont-Ferrand, France, a
corporation of France

Application May 9, 1932, Serial No. 610,272
In France May 30, 1931

2 Claims. (Cl. 295—7)

The present invention relates to improvements in guide flanges for railway vehicles, and has for an object to provide an improved guide flange that will be noiseless in operation.

5 The metal flanges now quite generally used on railway vehicle wheels have the disadvantages of being noisy and of wearing out quickly. It is the purpose of the present invention to do away with these disadvantages.

10 In accordance with the invention, the guide flange carries an anti-vibrating material presented to the rail head to avoid the contact of metal to metal, thereby eliminating noise, and at the same time, such material is replaceable, whereby 15 the anti-vibrating substances may be replaced with comparatively small expense without having to replace the entire guide flange.

With the foregoing and other objects in view, the invention will be more fully described hereinafter, and will be more particularly pointed out in the claims appended hereto.

In the drawing, wherein like symbols refer to like or corresponding parts throughout the several views,

25 Figure 1 is a transverse section taken through a portion of a rail head and vehicle wheel showing an improved guide flange constructed according to the present invention.

Figures 2, 3 and 4 are fragmentary vertical sections of modified forms of guide flanges.

Referring more particularly to the drawing, 1 designates a pneumatic tire, such for instance as employed on rail cars, which pneumatic tire is mounted upon a rim 2, having a guide flange 3 extending outwardly therefrom along one side of the tire and adapted to cooperate with the rail head 4 to maintain the vehicle on the track.

This guide flange 3 carries at its outer portion, which projects beyond the perimeter of the tire 1, a body of some anti-vibrating material 5, such for example as ebonite, hard rubber, bakelite, hardwood, etc. Such materials as ebonite, hard rubber, bakelite and some other substances are mouldable, and when fluid or plastic, may be poured or moulded into a recess or cavity provided in the guide flange. This cavity is shown to be embraced between inner and outer walls 11 and 12, which are preferably undercut in order to give the body 5 of the anti-vibrating material a firm purchase and an interlocking engagement with the rail flange. The body of material 5 thus becomes a moulded ring extending about the wheel, and in position to engage the rail head 4. The exposed face *a* of the ring or body of material 5 is adapted to come into contact with the

lateral face *b* of the rail 4, and in so doing noises and vibration are diminished and eliminated. The body of material 5 will project out beyond the cavity, so as to permit contact with the rail head without allowing any part of the guide flange to cause a metal to metal contact.

Referring more particularly to Figure 2, the body 5^a of anti-vibrating or sound deadening material is held in place by an inner removable wall or flange 11^a, bolted, riveted, or otherwise secured, as indicated at 7, to the guide flange 3^a. The outer wall 12^a may be permanent, as in Figure 1.

In accordance with this Figure 2, an organic material like hardwood, which is not subject to pouring and moulding, may be used and may be cut and shaped to fit the cavity or recess and put in place after the removable wall 11^a has been removed. This wall 11^a is subsequently replaced and fastened to the guide flange 3^a, thus securely holding the organic ring 5^a in place. The inner wall 11^a may be circular and extend all about the inner side of the substance 5^a. Its removal facilitates the replacement of the ring 5^a when worn.

Referring more particularly to Figure 3, in this example, the guide flange 3^b is devoid of any recess or cavity and may be simply made plain. The sound deadening material or substance 5^b may be simply placed against the plane surface of the guide flange and secured directly thereto, as by the use of rivets 8, bolts, or other fastening means. The heads of the rivets will preferably be countersunk in the body or substance 5^b, so that portions of the substance will extend beyond the rivet heads for the purpose of preventing metal to metal contact with the rail head.

Coming now to Figure 4, the sound deadening substance or ring 5^c is contained in a recess or cavity formed in a detachable member 9, and such detachable member is removably secured to the guide flange 3^c, as by the use of bolts, or other fastening means 10. In this case, the sound deadening material 5^c will be moulded into the cavity in the member 9.

It will be apparent that with the use of the invention, silence will attend the movement of the guide flange upon the side of the rail head. Moreover, the substance 5 will, beside having sound deadening qualities, also preferably possess a certain resilience, which will reduce shocks caused by the flange encountering the rigid rail head.

With the ordinary railway wheel, when the guide flange is worn, the entire wheel must be replaced, but with the use of the present inven-

tion, in the event of wear, it is only necessary to replace the substance or ring 5, or, in the case of Figure 4, the member 9 carrying the substance 5. The remainder of the guide flange is retained and is not subject to wear or deterioration.

It will be obvious that various changes in the construction, combination and arrangement of parts could be made which could be used without departing from the spirit of my invention, and I do not mean to limit the invention to such details except as particularly pointed out in the claims.

Having thus described my invention, what I claim and desire to secure by Letters Patent of the United States is:—

1. In a railway vehicle wheel, a guide flange therefor having a recess disposed in the side thereof facing the rail, and a sound deadening material seated in said recess and projecting beyond in position to engage the rail, a portion at least of the side walls of said recess being removable.

2. In a railway vehicle wheel, a guide flange structure including an outer overhanging wall, a ring of sound deadening material placed against said flange and said wall, and a removable wall engaged with the guide flange and with a portion at least of said sound deadening ring.
